Patented Oct. 28, 1975

237,368

BICYCLE WHEEL REFLECTOR

Richard A. Disbrow, Battle Creek, Mich., James E. Hadley, Wichita, Kans. and Thomas M. Stiles, Blue Springs, Mo., assignors to Rupurt Manufacturing Company, Blue Springs, Mo.

Filed July 10, 1974, Ser. No. 487,310

Term of patent 14 years

Int. Cl. D10—06

U.S. Cl. D10—111

FIG. 1 □.

FIG. 2.

FIG. 3.

FIG. 4.

FIG. 1 is a perspective view of a bicycle wheel reflector according to our new design;

FIG. 2 is a front elevation view of the reflector of FIG. 1;

FIG. 3 is a right side elevation view of the reflector of FIG. 1;

FIG. 4 is a left side elevation view of the reflector of FIG. 1;

FIG. 5 is a top view of the reflector of FIG. 1;

FIG. 6 is a bottom view of the reflector of FIG. 1;

FIG. 7 is a perspective view of a modification of a bicycle wheel reflector according to our new design;

FIG. 8 is a front elevation view of the reflector of FIG. 7;

FIG. 9 is a right side elevation view of the reflector of FIG. 7;

FIG. 10 is a left side elevation view of the reflector of FIG. 7;

FIG. 11 is a top view of the reflector of FIG. 7; and FIG. 12 is a bottom view of the reflector of FIG. 7.

We claim:

The ornamental design for a bicycle wheel reflector, substantially as shown and described.
